UNITED STATES PATENT OFFICE.

BARNET RUDOLFF, OF BAYONNE, NEW JERSEY, ASSIGNOR TO FANNIE DORISON, OF JERSEY CITY, NEW JERSEY.

LUBRICATING-PINTLE.

1,168,568.

Specification of Letters Patent. Patented Jan. 18, 1916.

Application filed December 3, 1914. Serial No. 875,391.

To all whom it may concern:

Be it known that I, BARNET RUDOLFF, citizen of the United States, residing at Bayonne, in the county of Hudson and State of New Jersey, have invented certain new and useful Improvements in Lubricating-Pintles; and I do hereby declare the following to be a full, clear, and exact description of the invention, such as will enable others skilled in the art to which it appertains to make and use the same.

My invention relates to improvements in lubricating pintles for butts and hinges and resides in the provision of a pintle which is constructed so that a lubricant may be conveyed to all parts of the joints of the hinge so as to prevent squeaking and reduce the wear on the barrels and pintle to a minimum.

Another object is to provide a simple and effective lubricating pintle that consists of a small number of parts, is reliable and effective in operation and which is inexpensive to manufacture.

The above and additional objects are accomplished by such means as are illustrated in the accompanying drawings, described in the following specification and then more particularly pointed out in the claims.

With reference to the drawings, wherein I have illustrated the preferred embodiment of my invention as it is reduced to practice, and throughout the several views of which similar reference numerals designate corresponding parts—

Figure 1 is a vertical sectional view of another modified form of my invention, Fig. 2 is a detail side elevation of the head or knob of the modified form illustrated in Fig. 3, and Fig. 3 is a top plan view of the pintle in Fig. 3 with the head or knob removed.

Referring to the drawings D designates as an entirety a pintle which comprises a cylindrical body 12 and a removable knob or head 13. The body 12 is hollow or in other words a tubular cylindrical barrel body is provided and lubricant discharge openings 14 are provided at spaced points on

the body so as to lubricate all hinged parts 50 of a hinge.

A tubular extension 15 is carried by the head 13 and is arranged to extend within the tubular body 12 of the pintle D. A vertical oil passage 16 is formed through the head or 55 knob 13 and communicates with the tubular portion 15. The member 15 is preferably formed integral with the head or knob 13. It will be readily seen that a lubricant may be poured into the hollow or tubular member 60 12 which is provided with a bottom wall 17 and will be discharged through the openings 14 so that all parts of the hinge to which the pintle is attached may be properly lubricated.

With reference to the foregoing description and accompanying drawings it will be readily seen that I have provided simple and effective lubricating pintles for butt hinges that may be cheaply manufactured and will 70 prove effective in operation.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as claimed.

What is claimed is:—

1. A hinge pintle including a tubular body having one end closed and a knob on the open end of the tubular body, said knob having a passage formed therethrough communicating with a tubular body, said body having discharge openings opening out upon the outer face thereof and communicating with the interior thereof.

2. A hinge pintle, comprising a tubular body having one end closed and being provided with openings communicating with the outer face thereof and the interior of the body, a knob, a tubular extension carried

by said knob and arranged to extend into the open end of said body, said knob having a lubricating passage formed therethrough and communicating with the tubular extension.

3. A hinge pintle including a tubular body, and a knob removably mounted upon one end of said body, said knob having a passage formed therethrough communicating

with the body, and said body having discharge openings formed therein.

In testimony whereof I affix my signature in presence of two witnesses.

BARNET RUDOLFF.

Witnesses:

JULIA RUDOLFF,
DORA RUDOLFF.
